UNITED STATES PATENT OFFICE

164,392

SPECTACLE FRONT

Harry Weissman, New Hyde Park, N.Y.

Application January 18, 1951, Serial No. 13,866

Term of patent 14 years

(Cl. D57—1)

To all whom it may concern:

Be it known that I, Harry Weissman, a citizen of the United States and resident of New Hyde Park, in the county of Nassau and State of New York, have invented a new, original, and ornamental Design for a Spectacle Front, of which the following is a specification, reference being had to the accompanying drawing, forming a part thereof.

Fig. 1 is a top plan view of a spectacle front, showing my new design.

Fig. 2 is a front elevational view of the spectacle front.

The dominant features of my design reside in the portions shown in full lines.

I claim:

The ornamental design for a spectacle front, substantially as shown and described.

HARRY WEISSMAN.
